UNITED STATES PATENT OFFICE.

ROBERT R. SMITH, OF PHILADELPHIA, PENNSYLVANIA, ASSIGNEE TO MILLER LOCK COMPANY, OF PHILADELPHIA, PENNSYLVANIA, A CORPORATION OF PENNSYLVANIA.

VACUUM-CLEANER.

1,140,284.

Specification of Letters Patent. Patented May 18, 1915.

Application filed January 9, 1912. Serial No. 870,208.

To all whom it may concern:

Be it known that I, ROBERT R. SMITH, a citizen of the United States, residing in the city and county of Philadelphia, State of Pennsylvania, have invented a new and useful Vacuum-Cleaner, of which the following is a specification.

My invention consists of an improved vacuum cleaner in which the suction device is operated by propelling the cleaner over the surface to be cleaned.

It further consists of improved means for applying the power from propelling the cleaner to the suction device.

It further consists of improved construction of the suction device.

It further consists of improved means for connecting the suction-nozzle to the vacuum chamber.

It further consists of improved construction of dust-bag support.

It further consists of other novel features of construction, all as will be hereinafter fully set forth.

The annexed drawings and the following description set forth in detail one mechanical form embodying the invention, such detail construction being but one of various mechanical forms in which the principle of the invention may be used.

In said annexed drawings—Figure 1 represents a perspective view of my improved vacuum cleaner. Fig. 2 represents a longitudinal vertical section of the cleaner. Fig. 3 represents a longitudinal horizontal section of the cleaner. Fig. 4 represents a transverse section of the cleaner through the rear portion of the vacuum chamber and looking rearward. Fig. 5 represents an axial section on an enlarged scale, of one of the pistons. Fig. 6 represents an enlarged sectional detail view of a portion of the forward end of the vacuum chamber. Fig. 7 represents an enlarged face view of the cap for the vacuum chamber. Fig. 8 represents a diametrical section of such cap. Fig. 9 represents a rear view of the nozzle-structure. Fig. 10 represents a sectional detail view of the handle-socket. Fig. 11 represents a detail view of one of the intake valves for the pump-cylinder.

Similar numerals of reference indicate corresponding parts in the figures.

Referring to the drawings, the numeral 1 indicates a casing of sheet-metal, substan-

tially rectangular in longitudinal and cross section and having its upper side-edges rounded and its bottom open. An arched reinforcing strip or yoke, 2, is transversely secured in said casing near its rear end, and plates, 3, stamped from sheet-metal to form annular ball-races, 4, are secured to this arched yoke. A crank-shaft, 5, has cupped annular ball-races, 6, secured upon its ends to bear upon anti-friction balls, 7, confined between the ball-races. Two wheels, 11, are secured, one at each end of the shaft, and each of said wheels is formed from dished sheet-metal disks, 12, having their edges stamped or drawn to form inwardly-projecting flanges, 13, which form the rim of the wheel but do not completely meet and form a circumferential slot or space. The dished centers, 14, of the disks are secured together and to a circular, axial portion, 15, of one cheek of each crank, 16, by means of rivets or bolts, 17. Tires, 18, of rubber or similar material, fit upon the peripherally slotted wheel-rims and are held against lateral displacement by the yielding rubber entering the slot. Split bushings, 19, of indurated fiber or similar material fit upon the pins, 20, of the cranks, and pitmen, 21, have heads, 22, formed with semicircular portions, 23, engaging the bushings, and open sides having projecting ears, 24, through which cotter-pins, 25, pass to confine the bushings in the heads.

A forwardly tapering vacuum chamber, 26, of sheet-metal, which constitutes the dust-separator chamber, is secured by screw-bolts, 27, and thumb-nuts, 28, to the main casing, said bolts passing through a forward wall, 29, of the casing and a rear wall, 30, of the vacuum chamber, and two cup-shaped seamless cylinders, 31, preferably drawn or stamped from sheet-metal are secured with their integral heads to the rear wall of the vacuum chamber and project, when the vacuum chamber and casing are assembled, through openings, 32, in the forward wall of the casing. The rear wall of the vacuum chamber has openings, 33, which register with openings, 34, in the heads of the cylinders. Valves, 35, of leather, rubber or similar material, and consisting each of a circular central portion, 36, and ears, 37, sliding upon headed posts, 38, projecting rearward from the heads of the cylinders, play over the flat seats around ports or open-

ings in said heads to form inwardly or rearwardly opening valves.

Pistons, 39, are drawn or stamped from sheet-metal into seamless cylindrical cup-shaped, each having its closed integral end, 40, of less diameter than the body of the piston to form a shoulder. A cup-packing, 41, of indurated fiber or similar material is placed upon the closed head of the piston, 10 and an annular yielding gasket, 42, bears against said packing, having an annular rib, 43, formed in a disk, 44, bearing against it. A bolt, 45, having a nut, 46, upon it, secures said parts together, passing through central 15 openings in the piston-head, packing and disk, and said bolt is prevented from turning by an abutment, 102, such as a drop of solder, bearing against its head, which is formed with two ears, 47, between which the 20 forward end of the piston-rod is pivotally secured, preferably upon a cotter-pin, 48. The piston-head, cup-packing and disk may be further secured and clamped together by one or more screw-bolts, 49. The piston- 25 head, cup-packing and disk have registering openings, 50, and a flexible, inwardly-opening flap-valve, 51, is secured upon the rear face of the piston-head to cover the valve-opening thus formed.

30 An annular seat-frame is formed on the forward end of the tapering vacuum chamber by a ring formed with a flange, 52, secured to the end of the vacuum chamber, an annular rounded seat, 53, and an inwardly 35 projecting flange, 54. Screw-bolts, 55, are secured in the outer end of the vacuum chamber and in the rearwardly projecting flange, 52, and said bolts preferably are so relatively arranged that the bolts at the 40 upper side of the vacuum chamber project at a distance from each other different from those at the under side, for the purpose to be later referred to. A cap, 56, fits with a flange, 57, over the seat-frame of the hood, 45 and is formed with an annular recess, 58, into which fits an annular gasket, 59, which bears against the annular seat of the frame when secured over the same. The flange of this cap is formed with bulges, 60, having 50 open-ended slots, 61, terminating in round and bevel-edged openings, 62, which slots and openings register with the bolts upon the seat-frame, so that the cap may be fitted upon said frame by sliding the slots upon 55 the bolts until the latter project through the openings. Tapered thumb-nuts, 63, fit upon the radiating bolts and, when screwed inward upon the bolts and bearing with their tapering sides within the openings in 60 the flange of the cap, such tapering nuts will draw the cap inward against the seat and secure the cap tightly upon the same. A dust-bag, 64, of material permeable to air but impermeable to dust, has a ring, 65, at 65 its mouth, which ring rests upon the annu-

lar, inwardly-projecting flange of the seat-frame and is held against the same by the annular gasket.

A nozzle, 66, having a narrow slot, 67, and a duct, 68, similar to nozzles usually employed in vacuum cleaners, has a circular head, 69, from the flat rear face of which projects a nipple, 70, to project centrally through a circular opening, 71, in the cap. Said nipple has two diametrically projecting lugs, 72, and the opening in the cap has two radial slots, 73, into which the lugs may be inserted to engage under the rim of the opening when the nozzle and head is rotated one-quarter turn. The cap is formed with an annular rib, 74, and a gasket, 75, is interposed between said rib and the flat rear face of the head of the nozzle. For the purpose of tightening the fit of said rib and gasket, the rims of the opening in the 80 cap are deflected between the radial slots to form cam-surfaces, 76, beneath which the lugs bear. The circular head of the nozzle-structure has a radially projecting hook, 77, which engages a screw-bolt, 78, upon the 85 cap, and may be clamped in such engaged position by a tapering knurled nut, 79, by means of which the nozzle will be held in true operative position.

A wire-frame, 80, is secured upon the 95 front-face of the rear wall of the vacuum chamber and has eyes, 81, formed at its ends, which fit upon two of the upper screw-bolts securing the vacuum chamber to the main casing, and an eye, 82, formed upon its 100 transverse bar, fitted upon the lower screw-bolt,—all eyes being held in place upon said bolts by washers, 83, upon the bolts and by the nuts upon the same. Loops, 84, are formed upon the side-bars of the frame and 105 extend across and outward from the intake valve-openings to form guards preventing the dust-bag from being drawn into the latter by the suction of the pump-cylinder.

A bail, 85, of strap-metal, is pivoted near its ends upon pins, 86, extending from circular plates, 87, secured upon the sides of the main casing, and said plates have stops, 88, against which said bail may rest when tilted rearward, and radial and tapering lugs, 89, which may engage correspondingly shaped grooves, 90, in the bail when the latter is raised in a vertical position. The middle of the bail is formed with a loop, 91, and a socket, 92, for the handle, 93, is 110 clamped upon the straight portion of said loop. Said socket consists of two portions, 94, formed from pressed or stamped sheet-metal and shaped to form two cylindrical halves, 95, of a socket, two tapering parts, 96, two flat shank-portions, 97, and two doubly bent clamp-portions, 98, which embrace the straight portion of the loop. The shank-portions are secured together by a rivet, 99, and a screw-bolt, 100, having a 115 120 125 130

thumb-nut, 101, passes through the socket-halves and through the handle therein, securing said halves together and securing the handle in the socket.

5 In practice, the cleaner is propelled over the floor, carpet, rug, or whatever surface is to be cleaned. The yielding tires of the wheels are preferably roughened to insure turning of the wheels when the cleaner is 10 propelled, and the rotary motion of the wheels is conveyed through the cranks and pitmen to the pistons in the suction-cylinders to reciprocate said pistons. As said pistons are reciprocated, they reduce the air-pressure in the vacuum-chamber, creating 15 suction through the dust-bag and nozzle-structure, so that dust and other particles will be drawn through the nozzle into the dust-bag which, being permeable to air but impermeable to dust and other solid particles, will collect such dust and particles. The bag will be presented from being drawn in through the valve-ports in the rear wall of the vacuum chamber and in 20 the heads of the cylinders by the wire-frames. When the bag is so full of dust as to prevent the free passage of air through it and free and full suction at the nozzle, the cap may be removed from the end of the 25 vacuum-chamber by unscrewing the thumb-nuts sufficiently far to admit of the slots sliding off from the screw-bolts, whereupon the dust-bag may be removed and emptied. The bag may now be again inserted with its 30 ring resting upon the flange of the end-frame of the vacuum chamber and the cap may then again be fitted upon said frame and secured by the thumb-nuts. By arranging the slots and enlarged openings in 35 the flange of the cap and the screw-bolts upon the annular frame in such a manner that the distance between the slots and bolts across the top differs from the distance between the slots and bolts across the sides and 40 across the bottom, and the distance between the slots and bolts across the sides differs from that across the bottom, it is impossible to fasten the cap in any manner to the vacuum chamber excepting in such manner that 45 50 the nozzle will project downward when secured in the cap.

The fiber cup-packings on the pistons will admit of the pistons working in the cylinders without lubrication, and the rubber gaskets interposed between such packings and the metallic disks confining these parts, serve to deaden any rattling or other noise caused by the friction between the dry packings and cylinders. The screws passing through the disks, packings and piston-heads insure the true alinement of the valve-

ports or openings through the same, preventing turning of said parts. The arched yoke inside the casing reinforces the same at the point where the wheels are journaled. 65

The machine is easily dismantled by removing the cap from the front end of the vacuum chamber and unscrewing the thumb-nuts from the fastening-bolts, when the vacuum chamber may be separated from the 70 casing, the cylinders withdrawn from the pistons, and all parts of the machine are accessible for inspection, cleaning, repairing or replacement.

Substantially all parts of the cleaner are 75 formed from sheet-metal, stamped or drawn into shape, whereby a great saving in material and weight is attained, and very slight amount of finishing of the parts is required. The parts are few and simple, 80 and are easy to assemble and to dismantle.

Other modes of applying the principle of my invention may be employed for the mode herein explained. Change may therefore be 85 made as regards the mechanism thus disclosed, provided the principles of construction set forth, respectively, in the following claims are employed.

Having thus described my invention what I claim as new and desire to secure by Letters Patent, is:—

1. In a vacuum-cleaner, a casing, wheels journaled in said casing, a pump cylinder in said casing, a piston in said cylinder and operatively connected to said wheels, a 95 vacuum-chamber detachably secured to the front of said casing and arranged longitudinally in line with said pump cylinder and communicating with the intake of said pump cylinder, and a nozzle detachably secured to and communicating with said vacuum-chamber.

2. In a vacuum-cleaner, a casing having a forward wall, wheels mounted in said casing, a dust-separating vacuum chamber 105 having a rear wall juxtaposed to said casing wall, bolts passing through the front wall of the casing and the rear wall of the vacuum-chamber and provided with nuts for detachably clamping said walls together, a suction-device operatively connected to the wheels and supported within the casing in the rear of said vacuum-chamber to have its intake communicate with the vacuum-chamber through the walls, and a 110 suction-nozzle secured to the forward end of the vacuum-chamber and discharging into the same.

ROBERT R. SMITH.
